UNITED STATES PATENT OFFICE.

LOUIS CHARLES REESE, OF SAGINAW, MICHIGAN.

CHARGING AND DISCHARGING OF AUTOMATIC OVENS, PROOFING-CHAMBERS, AND THE LIKE.

1,220,456.

Specification of Letters Patent. Patented Mar. 27, 1917.

Application filed February 28, 1916. Serial No. 81,008.

To all whom it may concern:

Be it known that I, LOUIS CHARLES REESE, residing at Saginaw, in the county of Saginaw and State of Michigan, have invented 5 new and useful Improvements in the Charging and Discharging of Automatic Ovens, Proofing-Chambers, and the like, of which the following is a specification.

This invention relates to automatic baking ovens, proofing chambers and like apparatus through which the articles to be subjected to the process worked therein, are passed in a certain, predetermined time and in a circuitous—partly horizontal, partly 15 more or less vertical—route by endless chains, and consists in novel means of charging and discharging these apparatus.

The object of this invention is to perform these operations automatically and without 20 stopping the apparatus, in a most simple, effective and economic manner.

To this end, I place the articles to be treated or the containers holding them on trays which may also be formed by joining 25 rows of these containers by suitable means as iron bands, and suspend these trays from the chains carrying them through the apparatus by devices consisting of two parts automatically engaging with and disengaging 30 from each other, one part of these suspending devices being connected to the tray and working together with the other part attached to the chains. The suspending devices used in the example described in this 35 specification are composed of hooks attached to the trays and of rods or bars (herein called "crossrods") connecting the chains and adapted for the hooks to catch over. These crossrods are preferably mounted 40 rotatably in the chains or in blocks or the like attached thereto.

The loaded trays are conveyed into the apparatus by automatic means, usually an ordinary endless-band-conveyer, to a point 45 so determined and arranged that the crossrods connecting the chains, while passing upward in close proximity to the tray on the conveyer, are bound to engage with the hooks attached to the tray, and thus the tray 50 will be picked up from the conveyer, lifted upward and then carried through the apparatus.

The trays are discharged from the latter by depositing them on their downward passage on automatic means for carrying them 55

away, usually an endless-band-conveyer, passing underneath at a point so determined and arranged that the hooks attached to the tray are bound to disconnect themselves from the crossrods connecting the chains, 60 while traveling downward, whereupon the chains with the empty crossrods and the disconnected trays are quickly removed in different directions, the conveyer taking away the trays being so constructed and traveling 65 with such velocity that they cannot interfere with the chains, their appendixes or any other obstacles. At the charging and discharging points of the apparatus preferably sprocket wheels are installed for the 70 chains to run over in order to give to the latter, to the suspending devices and to the trays just picked up or to be disconnected, ample stability and the proper direction.

The feeding devices used hitherto for this 75 kind of apparatus made it necessary that the chains were stopped while the trays were charged or discharged, and the unavoidable consequences were jerks and shocks liable greatly to damage the more or less soft goods 80 in appearance, shape and size. This was especially the case in automatic baking ovens of this class.

The accompanying drawings, which serve for more fully explaining the novel features 85 and devices and the working of the invention, show the arrangement in its application to a proofing and baking apparatus used for pan bread.

Figure 1 is a side elevation of a tray, in 90 which double-hooks attached to the trays are so arranged as to be able to catch over the crossrods connecting the chains carrying the trays, and to thus suspend the latter from the former.

Fig. 2 represents a longitudinal section of 95 a tray showing the same hook arrangement as in Fig. 1, the connection to the chains and the wheel-supports of the crossrods.

Fig. 3 represents an arrangement for 100 transferring trays provided with double-hooks as in Fig. 1 and Fig. 2, from a proofing chamber to an oven, and Fig. 4 an arrangement for discharging the same from the latter.

The tray A consists of two rows of pans, a, containing the dough pieces to be proofed or baked. The pans are connected by iron bands, a₁ arranged at their longer sides and a₂ at their shorter sides. The crosspiece a₃ 110

(Fig. 2) serves to stiffen the structure. In Figs. 1, 2, 3 and 4 the tray A is provided at each narrow side with the stays B and B₁ bearing the double hook C adapted with either downward-bent arm, c₁ or c₂, to catch over the crossrod D connected at each end to the endless chains H and H₁, carrying the trays through the apparatus. The stays B and B₁ are fixed to the iron bands a₂ and end in circular plates b and b₁, provided with the stops b₂ and b₃. The pin b₄ passing through the center of the circular plates b and b₁, holds the stays B and B₁ together, leaving sufficient room between them for the ring c₃ of the hook C to turn and thus to regulate the position of the hook C in regard to the tray A so that the latter is kept horizontal, may either arm, c₁ or c₂, be used to suspend the tray from the crossrod D connecting the chains H and H₁. In order to prevent the tray from moving more freely than is necessary to obtain the result described and to avoid any possibility of its being upset, the oscillations of the stem c of the hook C are limited by the stops b₂ and b₃.

The arms c₁ and c₂ of the hooks C are arranged opposite to each other and vertical to the tray A and the crossrod D. Both the arms c₁ and c₂ and the crossrod D are so constructed that the former turn easily around the latter when the same is turned in its circuitous travel through the apparatus, the trays thus remaining always in a horizontal position.

The crossrod D is rotatably mounted in the chains H and H₁ which it connects, and rests between the latter and the hooks C, C₁—leaving sufficient play for the tray—on the loose wheels E and E₁ which revolve freely around D and run in the grooves f for E and f₁ for E₁ of the rails F and F₁. The latter are supported by the brackets G and G₁ fixed to the walls or structure of the apparatus.

The rails F and F₁ carry in this way the crossrod D and with it the chains H and H₁ and the tray A, while these chains travel more or less horizontally. When the direction of the chains is altered more or less to the vertical, or from the latter to the horizontal again, the crossrods, wheels and trays are carried by the chains H and H₁ running over and supported by the teeth of sprocket-wheels in the well known manner of apparatus of this kind.

In Fig. 3, O represents diagrammatically the sprocketwheel around which the chains H travel inside an oven before its charging opening, and P the sprocketwheel for the chains H before the discharging opening in a proofing chamber situated alongside the oven. The sprocketwheel O revolves around the axle o, and the sprocketwheel P around the axle p, both moving in the same direction as shown by the arrows. I is a hori-

zontal endless-band-conveyer driven by the rollers K and K₁ rotated around the axles k and k₁ in the direction of the arrows by suitable driving means, the carrying surface of the conveyer traveling from the proofing chamber toward the oven. The roller K is arranged within the proofing chamber well underneath the sprocketwheel P, and the roller K₁ within the oven underneath the sprocketwheel O. Adjacent to the roller K₁, reaching still farther into the oven, preferably a rest is arranged for the trays arriving there; it consists of the parallel, loose rollers L, L turning easily around their axles l, l supported by the bracket M. The carrying plane of the rollers L, L is slightly inclined from the conveyer I in a downward direction so that the trays arriving there from the latter easily slip down against the crossbar N and thus attain the correct position for the arms c₁ of the hooks C to slip over the crossrods traveling upward toward the same.

In the proofing chamber the chains H carrying the trays containing the fully proofed dough pieces ready for the oven, travel at first vertically downward, and then around the sprocketwheel P, where the trays are deposited on the conveyer I underneath, whereupon the chains take the empty crossrods to the charging place of the proofing chamber, to be reloaded with fresh trays. In order that the crossrods easily disengage from the hooks C when the trays reach the conveyer I, the trays are suspended from the crossrods by the arms c₂ of the hooks C.

When in its downward passage in the proofing chamber the tray A₁ reaches the position I of its crossrod D₁, the preceding tray A₂ with its crossrod D₂ has just attained the position II and is being dropped on the conveyer I, and the empty crossrod D₃ has reached the position III of the proofing chamber.

The tray A₃ which, while in the proofing chamber, has been attached to the crossrod D₃, has at the same time reached the position I within the oven, and resting on the roller platform L against the support N, is just being picked up by the crossrod D₂ engaging the arms c₁ of the hooks C of the tray. The tray A₄ which entered the oven previously to the tray A₃, has been lifted by the crossrod D₃ traveling upward onto the position II in the oven, while the empty crossrod D₁ is moving toward the platform L, ready to pick up and lift the tray A₂ as soon as it has arrived from the proofing chamber at the position I in the oven.

This cycle of operations is repeated continuously. For the exact working of the arrangement it is—of course—essential that the conveyer I travels with the correct speed for the rays coming from the proofing chamber to be picked up by the crossrods in the

oven, a result which easily can be attained by well known means.

The trays can only be attached to the crossrods which have to carry them, when 5 the opening of the hooks to engage with these crossrods, is turned toward the same, and the latter move in an upward direction toward the said hooks. After having been lifted from the conveyer or roller platform, 10 the trays are at once carried upward to be out of the path of the following crossrods and trays. The conveyer bringing the trays to the charging point and the empty crossrods ready to engage the hooks of the trays 15 travel therefore always in opposite direction to each other.

As the crossrods and hooks turn during their travel through the apparatus in order to keep the trays always upright and horizontal, the openings of the hooks will always point in the same direction as that in which they were placed over the crossrods.

In order to discharge the trays, the chains and crossrods from which the trays are suspended, must travel downward, not only until the trays have been deposited on the conveyer underneath, but until the crossrods are quite out of reach of the hooks.

If, as in Fig. 3 showing the discharge of 30 the trays from the proofing cabinet, the arms of the hooks which connect the descending trays to the crossrods, point toward the interior of the discharging sprocketwheel P , the disengaged crossrods travel 35 at once in opposite direction to that of the conveyer taking the disengaged trays away, and the exact velocity of this conveyer is immaterial as long as it runs quickly enough to obtain the desired result. But, when, as 40 in Fig. 4, the arms of the hooks which connect the descending trays to the crossrods point outward the discharging sprocketwheel, the disengaged crossrods and the conveyer taking the disconnected trays away, 45 move in the beginning in the same direction, and in this case the arrangement and movements of the conveyer must be such as to prevent the trays, its accessories and the crossrods from interfering with each other.

50 Fig. 4 shows the latter arrangement. O_1 represents diagrammatically the discharging sprocketwheel of the oven, revolving around its axle o_1 . The chains H travel in the direction of the arrows, downward at 55 the right hand side of the sprocketwheel where the trays containing the baked bread ready to leave the oven, arrive, then around the lower part of the sprocketwheel O_1 and upward at the left hand side where the crossrods are empty. The conveyer carrying away the disconnected trays from underneath the sprocketwheel O_1 , consists of 60 two parts:—a quickly moving endless-band-conveyer Q worked in the ordinary way by 65 rollers of which in the drawing that near-

est to the sprocketwheel, R , rotated around its axle r by suitable driving means, is shown, and a stationary gravity conveyer formed by the loose rollers Q_1 revolving around their axles q and supported in the 70 bracket like staging q_1 . The carrying surfaces of the two conveyers are arranged in such a manner that the trays leaving the roller conveyer Q_1 easily slip over onto the quickly moving band conveyer Q . The 75 trays are suspended from their crossbars by means of the arm c_1 of the double hooks C as they were charged into the oven, see Fig. 3.

When the upmost, arriving tray A_1 suspended from the crossrod D_1 is at the position I, the preceding tray A_2 suspended from the crossrod D_2 is in the position II, just settling down on the roller conveyer Q_1 . At the same time the tray A_3 which preceded A_2 , has been disconnected from the crossrod D_3 , is in position III^a on the band conveyer Q , being quickly carried away, and the crossrod D_3 is in position III on the sprocketwheel, while the preceding empty 90 crossrod D_4 is at the position IV, traveling upward to the charging point of the oven.

The carrying surfaces of the conveyers Q and Q_1 are arranged at such a distance underneath the discharging sprocketwheel O_1 , and the endless-band-conveyer Q is rotated at such a speed that the empty crossrods passing on the chain H around the lower part of the sprocketwheel O_1 cannot interfere with the trays A or their hooks C moving on the conveyers in the same direction. 95

When in the position II on the sprocketwheel the tray A_3 had settled on the roller conveyer Q_1 and, traveling along the same, pushed by its disconnected crossbar D_3 , arrived at the position III^a on Q_1 , the crossbar D_3 was in the position III^x on the sprocketwheel and completely free from the hook C in any position of its arms c_1 and c_2 100 as shown in dotted lines. The tray A_3 then entered at once the conveyer Q which quickly moved into the position III^a thereon, thus leaving far behind at the position III the disconnected crossbar D_3 which has 110 the last chance of interfering with the hooks of the tray A_3 when at the position III^{xx}.

When the crossbar D_3 was at the position III^x on the sprocketwheel, the previously disconnected crossbar D_4 was at the 120 position IV^x thus beyond any possibility of colliding with the tray A_3 or its hooks. The same result may be obtained by other means; for instance the gravity conveyer may be omitted, the endless-band-conveyer prolonged accordingly instead and arranged to travel with two speeds slowly—with the same velocity as the crossbars move on the sprocket wheel between the positions II and III^x, and quickly when the latter point has 125 130

been reached so that the tray is in position III^a on the conveyer when the crossbar has arrived at the position III on the sprocket-wheel.

5 I do not limit myself to the exact construction and arrangement of the devices shown in Fig. 4 or in any other of the accompanying drawings, as the same may be varied without leaving the principles of 10 their construction and arrangement as defined in the claims attached to this specification.

When a single apparatus is to be charged and discharged, a single hook will serve 15 both operations; but when a tray is to be transferred from one apparatus to another one adjoining it, as shown in Fig. 3, a double hook is the most suitable device.

I claim:

20 1. In devices for charging and discharging apparatus of the kind described, the combination with the trays holding the articles to be treated, of crossrods connecting the chains moving the said trays through 25 the apparatus, of hooks attached to the trays and so constructed as to turn loosely around the said crossrods when suspended from same, thus always keeping the said trays in a horizontal position, and of conveyers arranged in the apparatus at points, where the hooks of the trays situated on the said conveyers are bound to engage with and disengage from the said crossrods.

2. In devices for charging and discharging 35 apparatus of the kind described, the combination with the trays holding the articles to be treated, of hooks attached to each end of the trays and adapted to automatically engage with and disengage from crossrods rotatably mounted in and connecting the two chains traveling in the same direction and at the same speed through the apparatus, and conveyers arranged therein at points, where the hooks of the trays situated on the said conveyers are bound to engage with and disengage from the said crossrods.

3. In devices for charging and discharging 50 apparatus of the kind described, the combination with the trays holding the articles to be treated, of hooks attached to each end of the trays, of crossrods rotatably mounted at their ends in and connecting two chains traveling through the apparatus 55 in the same direction and at the same speed, the said crossrods being so adapted and arranged that the hooks of the said trays engage with the said crossrods, when the latter pass by in an upward direction, and that 60 the hooks of the said trays disengage from the said crossrods, when the latter pass by in a downward direction.

4. In devices for charging and discharging 65 apparatus of the kind described, the combination with the trays holding the arti-

cles to be treated, of hooks attached to the said trays, of crossrods rotatably mounted in and connecting the chains moving the trays through the apparatus, of loose wheels rotatably mounted on the said crossrods, of 70 rails supporting these wheels and so arranged in the apparatus as to secure to the chains the right direction of travel and stability, and of conveyers arranged in the apparatus at points where the hooks of the 75 trays, when on the said conveyers, are bound to engage with the said crossbars passing by in an upward direction, and to disengage from the said crossbars passing by in a downward direction.

5. In devices for charging and discharging apparatus of the kind described, the combination with the trays holding the articles to be treated, of hooks attached to the ends of these trays, of crossrods rotatably 80 mounted in and connecting two parallel endless chains moving the trays through the apparatus, and adapted and arranged to engage with and disengage from the hooks of the trays, of loose wheels rotatably 85 mounted on the said crossrods and running in the grooves of rails supported by brackets fixed to the framework of the apparatus and thus carrying the chains, crossbars and trays, and of sprocket wheels over which 90 the chains run, when changing their direction, and then carrying the crossrods, loose wheels and trays, one or several of these sprocketwheels being rotated by suitable driving means and thus propelling the 100 chains through the apparatus, one sprocket-wheel being arranged at the charging point of the apparatus for leading the empty crossrods upward in order to engage with the hooks of the trays carried into the apparatus by a conveyer; and another sprocket-wheel being placed at the discharging point of the apparatus for leading the trays holding the treated articles downward, in order to disengage their hooks from the crossrods 110 of the chains and to deposit the trays being disconnected on the conveyer taking them out of the apparatus.

6. In devices for charging and discharging apparatus of the kind described, the combination with the trays holding the articles to be treated, of hooks attached to the ends of these trays by stays, of crossrods rotatably mounted at their ends in and connecting two chains traveling in the apparatus in the same direction and at the same speed, and adapted and arranged to engage with and disengage from the hooks of the said trays, and of conveyers carrying the articles to be treated into and the treated articles out of the apparatus and consisting of two parts one being an endless-band-conveyer, and the other being composed of loose rollers placed in alinement at a point of the apparatus where the crossrods and chains 125 130

pass by, when the trays are to be connected to the said crossrods, in an upward direction, and when the trays are to be disconnected from the said crossrods, in a downward direction.

7. In devices for charging and discharging apparatus of the kind described, the combination with the trays holding the articles to be treated, of stays fixed—two to each end of these trays and ending in circular plates, of double hooks consisting of two opposite equal arms and provided with a circular opening at the end of their stem, of pins, each connecting two of the said stays and carrying between the latter the said hook by the opening in its stem, of stops provided at the circular top-plates of the hooks to limit the play of the latter to that necessary for keeping the trays in a horizontal position, may one or the other of the arms of the said hooks be used, and of crossrods rotatably mounted at their ends in and connecting two endless parallel chains carrying the trays through the apparatus, and adapted and arranged to engage with or disengage from either arm of the said double hooks.

8. In devices for charging and discharging apparatus of the kind described, the combination with the trays holding the articles to be treated, of hooks attached to the trays, of crossrods rotatably mounted in and connecting two parallel, endless chains moving the trays through the apparatus, of sprocketwheels driven by suitable means and propelling the chains, of means for supporting the trays to be charged into the apparatus, of a sprocketwheel arranged above the said support at such a point that the empty crossrods led upward by the said sprocketwheel engage with the hooks of and thus pick up the trays on the said support, of a conveyer taking the trays holding

the treated articles out of the apparatus and of a sprocketwheel arranged above the said conveyer at such a point that the crossrods with the trays suspended therefrom led downward by the said sprocketwheel disengage from the hooks of the trays settling on and carried away by the said conveyer.

9. In devices for transferring articles from one apparatus to another apparatus of the kind described, the combination with trays holding the articles, of two systems—one for each apparatus—of parallel endless chains propelled by sprocketwheels at the required speed and carrying the trays through their respective apparatus, of crossrods rotatably mounted in and connecting the said chains, of hooks attached to the trays, of a sprocketwheel leading the crossrods carrying the trays with the treated articles downward before the outlet of the first apparatus, of a sprocketwheel arranged inside the second apparatus before its charging opening and leading the empty crossrods upward, and of a conveyer traveling in the direction from the first to the second apparatus and arranged at one end underneath the discharging sprocketwheel of the first apparatus at such a point that the hooks of the trays settling on and carried away by the conveyer disconnect from the crossrods move away in a downward direction and are unable to interfere with the said trays, and at the other end underneath the charging sprocketwheel of the second apparatus at such a point that the hooks of the trays on the said conveyer engage with the empty crossrods traveling upward, the trays thus being lifted upward into the second apparatus for being treated therein.
